UNITED STATES PATENT OFFICE.

OSCAR C. KAVLE, OF SYRACUSE, NEW YORK, ASSIGNOR TO WALLACE M. WEEKS AND JOHN A. PEASE, OF SKANEATELES, NEW YORK.

EXPANDER FOR BOTTLE CLOSURES.

Application filed February 25, 1926. Serial No. 90,710.

This invention relates to bottle capping machines and has for its particular object to provide novel, simple and effective means for expanding and compressing portions of the bottle closure during the final capping operation, for obviating warping and distortion of the closure, as well as for effecting the snug seating of the closure in the recess of the bottle mouth, for preventing loosening or displacement of the closure. A further object is to provide an expandable ring, said ring being supported by the plunger that effects the capping, said ring being split radially for providing a plurality of similar segments, the said segments being resiliently bound together by simple tension means, which enables the segments to separate and expand radially when pressure is exerted axially against the ring, by the plunger, the said plunger being formed with a rigid complementary element which directly effects the displacement of said segments, the said ring being normally extended axially beyond the end of the plunger, and adapted to resiliently engage the plane medial portion of the closure in advance of the engagement of the closure by the plunger, for positioning and holding the closure concentric to the bottle mouth, while the plunger completes the capping work.

I attain these objects by the means set forth in the detailed description which follows, and as illustrated by the accompanying drawing, in which—

Figure 1 is a top plan view of a bottle capping machine. Fig. 2 is a side elevation and partial vertical longitudinal section, the section being taken substantially on a line 2—2 of Fig. 1. Fig. 3 is a bottom end view of the plunger head, showing the rigid expanding member. Fig. 4 is a central vertical section, taken on line 4—4 of Fig. 3. Fig. 5 is a bottom face view of the expandable segment ring; showing the same contracted. Fig. 6 is a top face view of the of the same; showing the conical socket which receives the conical member of the plunger. Fig. 7 is a side elevation of the segmental ring showing the groove for the tension member, and Fig. 8 is a bottom face view of the segmental ring, in which the segments are extended for expanding the ring, as shown in Fig. 2.

In the drawings, 2 represents generally a bottle capping machine comprising a hollow conical base 2', which receives, and holds the bottle, as 3, while the cap, as 4, is being applied by a vertically reciprocatable plunger 5. The plunger is supported and guided by a relatively long bearing 6 that forms a portion of a chambered body 6', which rises from the base 2'. At one side of the body 6', is disposed the usual cylindrical magazine 6", in which the caps 4 are stacked, and below the magazine is disposed a horizontal guide 2", which supports a reciprocatable cap-feeder 8, the latter being operatively connected with and being operable by the plunger 5, by means of a series of cranks and links, indicated collectively by the character A. The lower end of the plunger 5 is fitted with an inverted cup-shaped head 9, which reciprocates with plunger 5 to the extent indicated by the full and the dotted lines in Fig. 2. The upward stroke of the plunger 5 shifts the cap-feeding parts to the full line position of Fig. 1. This positions the head 9 above the plane of the cap-feeder 8 (see dotted lines in Fig. 1), and allows a fresh cap 4 to be delivered to the capping chamber 7, directly above the bottle 3. The downward stroke of the plunger and head forces the fed cap into the bottle mouth, until the cap finally comes to rest upon the annular ledge or shoulder 3", that forms the bottom of the recess 3^b, of the bottle mouth. The strokes of the plunger are necessarily rapid, and owing to certain inequalities of the molded recesses 3^b, and a certain amount of looseness which the working parts of machines of the class require, in order to enable them to perform rapid capping work, the caps 4, which according to the present showing are preferably made from relatively thin pliant sheets of pulp board, frequently become warped or otherwise distorted, which results in the imperfect sealing of the bottle mouth. Furthermore, caps that are not snugly seated in the recess 3^b of the bottle mouth, often jar loose and become detached, thereby exposing the contents of the bottles to the atmosphere, as well as to germs and dirt. To remedy these defects, and to insure the tight and uniform sealing of the bottle mouths, I provide novel and simple means,

by which the portions of cap 4, which tend to warp by the action of the plunger 5, are compressed and molded in a manner to conform to and snugly fit the angular portion 3^b of the recess 3^b, which comprises the annular ledge 3^c, and the adjacent vertical wall 3^d that merges into the flaring bead 3^e. This molding and compressing means consists of metal ring 10, which is split radially for forming a number of similar segments 10', the said ring preferably being formed with a circumferential groove 10^a, in which is disposed a flexible band 10^b, that exerts a normal tension that holds the segments 10' in close relation, as shown in Figs. 5, 6 and 7, and the said band being sufficiently flexible to permit the segments to be expanded radially, (see Fig. 8), for compressing and holding the cap 4 tightly against the angular walls 3^c-3^d of the said recess, during the final capping movement of plunger 5 and head 9. The bottom face of the ring 10 is formed with a plain circular recess or cavity 10^c, in which is disposed a disc 12, having a diameter substantially equal to that of said recess. By this arrangement the segments 10' may be drawn closely together by the normal tension of the band 10^b, while the disc 12 tends to hold the segments in a common plane for preventing collapse of the ring, as shown in Figs. 2 and 7. The disc 12 is perforated centrally to receive a screw 10^d, by which the ring 10 is operatively secured to the head 9 (see Fig. 2). The top face of the ring 10 is formed with a relatively deep conical socket 10^e, which receives a rigid male cone 9' that is mounted concentrically in the head 9, in line axially with the plunger 5 and the bottle 3. The pitch of the conical member 9' and that of the socket 10^e are preferably the same, the member 9' being of greater diameter than the diameter of the socket 10^e, so that when the ring 10 contacts with the disc portion 4' of the cap 4, and pressure is exerted downwardly by the plunger 5, the expansion or separation of the segments 10' is effected, as shown in Fig. 8, and by the full lines in Fig. 2. The normal diameter of the ring 10 is less than the diameter of the disc 4' of the cap, and the spacing of the cone 9' and the disc 12 is such as to permit the ring 10, to move axially towards the head 9 during its expansion. This axial movement of the ring 10 is facilitated by disposing the lower portion of the ring below the bottom plane of the head 9, as clearly shown in Fig. 2. By this construction and arrangement the ring 10 begins to expand an instant before the full force of the downward stroke of the head 9 is exerted for seating the cap 4. When the pressure exerted by the plunger is relaxed, the tension of the band 10^b contracts the segmental ring 10 and moves said ring away from the head

9, as shown by dotted lines in Fig. 2, in readiness for the next capping operation and so on.

The operation briefly is as follows:

The head 9 being rigidly affixed to the plunger 5 and the ring 10 formed of the segments 10' being movable axially of the plunger, projects below the confining disk 12, so that when the plunger is given its working stroke, the segments 10' first engage the bottle closure and are thereby held against movement axially of the plunger. The plunger then continues its downward movement independent of movement of the segments whereupon its cam 9' engages the segments and expands the latter, such expansion occurring an instant before the head 9 seats and exerts pressure upon the cap 4.

Having thus described my invention, what I claim, is

1. In an expander for bottle closures, a plunger, a head fixed to the plunger for movement therewith and formed to seat on the part of the closure which overlies the bead of the bottle mouth, expanding means, means fixed to the plunger and movable therewith to operate the expanding means, and means to limit downward movement of the expanding means, said expanding means being mounted on the plunger so as to move lengthwise of the plunger whereby upon operative movement of the plunger the expanding means is engaged with the bottle closure and supported thereby while the plunger is permitted to move independent of the expanding means so as to cause the operating means for the expanding means to engage and actuate the latter.

2. In an expander for bottle closures, a plunger, an inverted cup-shaped head fixed to the plunger, a conical member within the head fixed to the plunger, a disk secured to the plunger and disposed below said member in spaced relation thereto, a series of horizontally slid able segments in the head movable axially of the plunger, and being supported by said disk against downward movement, said segments having inclined faces engageable with the conical member so as to be slid outwardly thereby, and spring means to tension the segments.

3. In an expander for bottle closures, a plunger, a member fixed to the plunger for movement therewith, and formed to seat on the part of the closure which overlies the bead of the bottle mouth, a second member fixed to the plunger and spaced below the first member, a series of horizontally disposed slid able segments between the members, said members being also movable lengthwise of the plunger, and means fixed to and operable with the plunger to effect sliding of the segments.

In testimony whereof I affix my signature,
OSCAR C. KAYLE,
